DRINK MIXING AND DISPENSING DEVICE

Theodore M. Costakos, Minneapolis, Minn.

Application December 1, 1932, Serial No. 645,227
Renewed February 19, 1936

7 Claims. (Cl. 221—108)

My invention relates to improvements in drink mixing and dispensing devices of the character disclosed in Patent No. 1,810,554 issued to me June 16, 1931, in which a dispenser for powdered malted milk or other comminuted material and a motor driven drink mixer are combined in a unitary structure.

An object of my present invention is to provide a simple, attractive and efficient device of the instant nature which requires a minimum of time and effort in the use thereof.

More specifically it is an object of my invention to provide holding means for the mixing receptacle which supports said receptacle in protected position of disuse, as well as in operative position and which, in the latter position of said receptacle, serves to maintain electrical contact between self-separating switch elements electrically connected with the mixing motor, but which, in the position of disuse of said receptacle or upon removal thereof from the device, permits of the separation of said switch elements.

Another object of the invention is to supply a composite device of the present kind in which the dispensing structure, at each operation thereof, discharges the comminuted material in full predetermined measure and delivers such charges into the mixing receptacle in the various positions assumed thereby when supported through said receptacle holding means.

An additional object of the invention is to combine a mixing motor and dispenser in a unitary structure in such manner that the motor and dispenser each contribute in providing a closure for the mixing receptacle when it is supported in position of disuse by the receptacle holding means.

A further object of the invention is to provide in the dispensing structure, novel and effective agitating and feeding means cooperating to insure the delivery of the comminuted material in full predetermined quantity.

With the foregoing and other objects in view, which will appear in the following description, the invention resides in the novel combination and arrangement of parts and in the details of construction hereinafter described and claimed.

In the drawings, Fig. 1 is a front elevational view of a device embodying my invention; Fig. 2 is a side elevational view of the same, parts thereof being broken away to show the mechanical and electrical connections between the mixing motor and the dispenser structure; Fig. 3 is a bottom view of the standard of the device; Fig. 4 is a fragmentary sectional view in detail, the same being taken as on the line 4—4 of Fig. 1;

Fig. 5 is a view similar to Fig. 4, the same being taken as on the line 5—5 of Fig. 1; Figs. 6, 9, and 10 are sectional views taken, respectively, on the lines 6—6, 9—9, and 10—10 of Fig. 4; Figs. 7 and 8 are plan views of the standard as seen with the motor and dispenser structure removed therefrom; Fig. 11 is a fragmentary sectional view in detail, the same being taken as on the line 11—11 of Fig. 4; and Fig. 12 is a perspective view illustrating the measuring member in detail.

Reference being had to the accompanying drawings in which similar reference characters designate similar parts throughout the several views, it will be noted that the illustrated device includes a hollow standard A having a base 10 which affords a firm footing for the entire structure. The front wall 11 of the standard A is concave in cross-section, the wall 12 forming the back and sides of said standard being substantially semi-circular. At the top of the standard A is an open top shell-like head B including a bottom 13 integral with the wall 11 of the standard A and also including a wall-like flange 14 integral with said bottom 13, the interior of said head being in communication with the interior of the hollow standard proper. Supported by the standard A is a container C for malted milk or other comminuted material to be added to ingredients to be mixed into drinks. This container includes a lower part c having a cylindrical wall 15 and having an integral bottom 16, which caps the shell-like head B of the standard proper and over-reaches the front wall 11 thereof, said lower part c of the container C being anchored in place on said head B by means of screws 17 (Fig. 5) extending upwardly therethrough and threaded into the bottom 16 of the container. This container C further includes a tubular body 18 telescoped into said lower part c of the container, said body being fitted with a removable cover 19.

The front of the lower part c of the container C has a planiform face 20. A motor 21 formed with a similar face 22 at one side of the shell thereof is supported through said lower part c of said container. In mounting the motor 21 on said part c of the container, the face 22 of the former is brought against the face 20 of the latter, supporting studs 23 (Fig. 2) issuing from the shell of the motor being fitted into bores 24 in the container part c as shown in Fig. 2. Removable locking pins 25 inserted into vertical bores 26 in the container part c pass through transverse bores in the studs 23, the lower ends of said pins being threaded into the lower portions of the bores 26 which are internally threaded.

to receive them. The lower face 27 of the motor shell is flat and made flush with the lower face of the bottom 16 of the container part c for a purpose soon to appear.

5 Depending from the vertically disposed shaft of the motor 21 is a mixer stem 28 having a mixer head 29 thereon. A cup-like receptacle 30 in which a drink is to be mixed is brought into the position shown in Fig. 2, wherein the mixer stem 10 28 is received within the receptacle 30 and the curved wall of said receptacle is received within the concavity in the front wall 11 of the standard A. The ease with which the receptacle may be manipulated into and out of such position will be 15 readily apparent. To retain the receptacle 30 in its operative position as shown in solid lines in Fig. 2, I provide a holder therefor consisting of a pair of forwardly extending jaw-like arms 31, 32 oppositely curved to receive said receptacle 20 therebetween. These arms 31, 32 are pivoted at their inner ends in bearings 33 within the hollow standard A, the forward wall 11 of said standard being formed with a slot 34 therein to receive said arms 31, 32. Fingers 35, 36 on the 25 arms 31, 32, respectively, curve toward each other and overlap at their ends, the finger 35 occupying a position between finger 36 and the wall 12 of the standard A. These fingers 35, 36 have elongated registering apertures in their overlapping 30 portions and projecting through said apertures is a headed screw 37 which is threaded into the wall 12 of the standard. I provide a U-shaped spring 38 through the legs of which the screw 37 also passes. This spring is interposed 35 between the head of said screw 37 and the finger 36 of arm 32, and, exerting pressure against said finger 36, normally holds the arms 31, 32 in the position shown in Fig. 7 with the finger 36 of arm 32, abutting against the finger 35 40 of arm 31 and said latter finger in turn, abutting against the wall 12 of the standard A. Said arms 31, 32 are easily spread apart against the action of the U-shaped spring 38 to receive the receptacle 30, this operation being effected 45 simply by using a finger piece 39 on arm 31 to swing the same outwardly. Upon such movement of said arm 31, its finger 35, operating upon finger 36 of arm 32 and against the action of the spring 38, imparts an outward 50 swinging movement to said arm 32. Thus moved outwardly in opposite directions the arms 31, 32 are spread apart and the receptacle is easily passed open end foremost between said arms. Upon releasing the arm 31 both arms 31, 32 are 55 swung toward each other by the spring 38, which acts against the finger 36 of arm 32, finger 36, in turn, acting against the finger 35 of arm 31. The diameter of the receptacle 30 is such that it is firmly gripped by the arms 31, 32, before the 60 finger 35 reaches its limit stop which is constituted, as above indicated, by the wall 12 of the standard A.

Wires 40 and 41 are employed in furnishing electrical energy to the motor 21. At corresponding 65 ends, these wires 40, 41 are connected with a plug 42 (Fig. 3) secured in the base 10 at one side thereof, said plug having conductor prongs 43 extending outwardly from said base, said prongs being adapted to be received in the usual 70 manner in an electric socket member of conventional form. Said wires 40, 41 are threaded through the hollow standard A and connected with insulated spring terminals 44 (Fig. 8) situated in the head B of the standard A. A pair of 75 conductors 45 (Fig. 2) running through the bot-

tom of the container part c have terminals 46 at their inner ends contacting with the terminals 44 and also have terminals 47 at their outer ends which fit into an electric receptacle 48 (Fig. 2) built into the shell of the motor 21 for supplying current to the motor. 5

It being desirable that the motor 21 start and remain in operation when the receptacle 30 is in its operative position (Fig. 2) and that said motor stop when said receptacle is removed from that 10 position, I have devised means by which the circuit through the wires 40, 41 is automatically completed when the arms 31, 32 are spread apart far enough to accommodate the receptacle in its operative position and by which said circuit is 15 automatically interrupted when said arms are relatively nearer together. To accomplish this result a switch 49 (Figs. 7 and 8) is employed, the same being located within the head B of the standard C. This switch is cut-in the wire 40 20 and includes a body portion or block 50 of insulating material secured to the bottom 13 of the head B. Contacts 51 secured to the insulating block 50 are connected with the ends of said wire 40 where it is severed to permit of the interposition 25 therein of the switch. Companion contacts 52, electrically connected, are carried on a cross-head 53 which, in turn, is carried on the legs of a U-shaped link 54, said legs of said link being slidably mounted in the body block 50 of the 30 switch. An expansion spring 55 is interposed between said body block 50 and said cross-head 53. Unrestrained, this spring 55 slides the link 54 in the block 50 shifting the cross-head 53 away from said block and thus moving the contacts 35 52 from engagement with the contacts 51 on said block. Such action of said spring 55 is, however, countered by connecting the link 54 with the finger 36 of arm 32, said connection being made through the medium of an upstanding pin 56 40 caught at the upper end thereof within the bend of the link 54 and anchored at the lower end thereof on a lug 57 (Fig. 6) issuing from the finger 36. The action of the switch 49 in relation to the movement of the arms 31, 32 may be readily understood upon inspection of Figs. 7 and 8. In Fig. 8, the arms 31, 32 are held spread apart by the receptacle 30, in its operative position. With the arms 31, 32 thus relatively disposed, the link 54 of the switch 49 is drawn against the 45 action of the spring 55 sufficiently to engage the contacts 52 with the contacts 51 and thereby complete the motor circuit. Any closing movement of the arms 31, 32 as by the removal of the receptacle 30 therefrom or by the shifting of 50 said receptacle upwardly into inoperative position while still in the embrace of said arms, will release the link 54 to the action of the spring 55 55 and said spring will retract the link, causing the contacts 52 to be disengaged from the contacts 51 (Fig. 7) and thus breaking the motor circuit. 60

As previously indicated, the lower face of the bottom 16 of the container C is flush with the lower face 27 of the shell of the motor 21. This 65 construction is devised to supply a flat surface against which the lip of the receptacle 30 may abut when the receptacle is in the grasp of the arms 31, 32. Under this arrangement, the receptacle 30 may be conveniently accommodated 70 on the device itself and at the same time may be conveniently closed against the entry thereto of flies, dust or other foreign matter. A spring clip 58 may be secured to the lower face of the motor shell to engage the beaded lip of the receptacle 30 75

and aid the arms 31, 32 in holding said receptacle in its protected inoperative position with the mouth thereof closed by the container C and motor 21.

5. The receptacle 30 is of the usual frusto-conical form and being in such form permits the arms 31, 32 to close upon each other sufficiently to throw-off the switch 49 when said receptacle is thrust upwardly between the arms 31, 32 from operative position as seen in solid lines in Fig. 2 to protected inoperative position, as seen in Figs. 2 and 5; where the mouth of the receptacle is closed.

10. To prevent the lip of the receptacle 30 from catching in the slot 34 formed in the wall 11 of the standard for the arms 31, 32, I provide a closure plate 59 which fits into the concavity of the wall 11 and overlaps said slot 34 except at the ends thereof wherein the arms 31, 32 play, 20 as they open and close.

15. Depending from the bottom 16 of the container part c is a spout 60 which directs the comminuted material from said container into the receptacle 30 held in the grasp of the arms 31, 32. It is desirable that such material be dispensed in measured quantities and to that end I have incorporated within the container C a novel and effective mechanism for so delivering material from said container.

20. The lower part c of the container has a false bottom 61 spaced from the bottom proper 16, said bottom proper having an orifice 62 therein registering with the spout 60 and said false bottom 61 having an orifice 63 (Fig. 9) therein offset from 25 said first opening 62. Journalled concentrically in the bottom 16 and false bottom 61 of the container part c is an upright shaft 64 having an enlarged cylindrical portion or head 65, the lower end of which bears upon the upper surface of the 30 false bottom 61. Disposed within the space between the bottom 16 and false bottom 61 is a measuring member D, segmental in form, the construction of which is best seen in Fig. 12. This measuring member fits snugly between the bottoms 16 and 61 of the container part c and 35 includes an arcuate body 66 resembling a ring fragment. Integrally formed with the body 66 is a boss 67 having a bore 68 concentric with the inner surface of the wall 15 of the container part 40 c. Issuing radially outward from the body 66 intermediate its ends is a pair of spaced blades 68, 69. Formed integrally with the upper margins of the blade 69 and body 66 is an arcuate gate or closure 70 the same extending from said blade 69 to the adjacent end of said body. Integrally 45 formed with the lower margin of the blade 68 and the corresponding margin of the body 66 is a second arcuate gate or closure 71 which extends from said blade 68 to the adjacent end of the body 66. The bore 68 in the boss 67 receives the shaft 64 and a pin 72 passing through said boss 67 and shaft 64 locks the measuring member D to the shaft causing the one to turn with the other. The outer edges of the blades 68, 69 and 50 arcuate gates 70, 71 skirt the wall 15 of the container part c. The space between said blades 68, 69 and between said body 66 and the container wall 15 provides a pocket d, open at top and bottom thereof, said pocket corresponding cross-sectionally with the orifices 62 and 63 in the bottom 16 and false bottom 61, respectively, of the container.

55. Beneath the bottom 16 of the container is a second boss 73 (Fig. 4) which is keyed to the shaft 64 by means of a pin 74. Formed integrally with this boss 73 is an actuating lever 75 having

a finger piece 76 at the outer end thereof. This lever 75 extends through and plays in a slot 77 (Figs. 1 and 2) provided by forming a recess 78 (Figs. 7 and 8) in the upper edge of wall 14 of the head B of the standard. Said wall 14 at the forward extremity of said recess 78 constitutes a stop 79 limiting the forward movement of said lever 75 and a rubber bumper 80 (Fig. 7) anchored within said head B supplies a stop limiting the rearward movement of the lever 75. Normally, 10 said lever 75 is held against the rubber limit stop 80 by the action of a tension spring 81 (Fig. 10), one end of which is secured to the body 66 of the measuring member D and the other end of which is secured to the bottom 16 of the container part c. 15 With the lever 75 abutting against the limit stop 80, the pocket d in the measuring member D registers with the orifice 63 in the false bottom 61, the gate 70 at such time closing the orifice 62 in the bottom 16 and serving to prevent the entry of any outside foreign matter into the space between the bottom 16 and false bottom 61 of the container. With the lever 75 swung against the action of the spring 81 into the position, against the limit stop 79, shown in solid lines in Fig. 9 and in dotted lines in Fig. 10, the pocket d of the measuring member D is situated in registry with the orifice 62 in the bottom 16 of the container, the gate 70 at such time closing the orifice 63 in the false bottom 61. Thus, it will be understood, 20 that a dry granular or powdered material stored within the container C will gravitate through the orifice 63 in the false bottom 61 and fill the pocket d of the measuring member D when the actuating lever 75 is in its normal position. And, it will 25 also be understood that upon swinging said lever 75 forwardly to its limit stop 79, the said measuring pocket d will be shifted into registration with the orifice 62 in the bottom 16, through which orifice the contents of said pocket will gravitate 30 and be directed by the spout 60 into the receptacle 30 embraced by the arms 31, 32. The gate 70 closes the orifice 63 in the false bottom 61, when the measuring member D occupies the above described position in which it releases its charge of 35 material.

35. The comminuted materials ordinarily dispensed in devices of the present nature have a tendency to absorb moisture and thereby become more or less caked. It is therefore desirable that means 40 be provided to minimize the caking of the materials to be dispensed and that the filling of the measuring pocket d with such material be positively assured. To this end, I employ an agitator E within the container C. In the form illustrated, the agitator includes an upright stem 82 threaded at its lower end into the head 65 of the shaft 64. Spaced arms 83, in pairs, at right angles to each other, pass through and are supported by said agitator stem 82, the arms of each pair and the connecting reaches 84, joining the ends thereof, consisting of a single piece of wire. This agitator E oscillates upon the rocking of the shaft 64 and in so doing breaks its way 45 through the material in the container with the result that any tendency of the material to cake is effectively minimized. Cooperating with the agitator E in keeping the material to be dispensed in powdered or granular form is a ratcheting spider F. The principal function of said spider, 50 however, is to feed the material into the orifice 63 in the false bottom 61. Said spider F includes a hub 85 journalled on the head 65 of the shaft 64, the hub being formed with radial blades 86 in edgewise contact with the upper face of 55

the false bottom 61. Ratchet teeth 87 formed peripherally of said head 65, are engaged by a pawl 88 (Fig. 11) slidable in a hollow stem 89 issuing from the hub 85, said pawl being yieldingly pressed into engagement with the ratchet teeth 87 by means of a spring 90 interposed between the outer end of said pawl 88 and a plug 91 threaded into the bore of said stem. Upon the dispensing throw of the lever 75, the spider F remains stationary, but upon the return throw of said lever, when the pocket d in the measuring member D is being retracted for a fresh charge of material, said spider F is turned through one of the ratchet teeth 87 and pawl 88 in a counter-clockwise direction as seen in Fig. 9. The blades 86 of the spider receive material between them at the bottom of the container and shift such material a step at a time toward the orifice 63 in the false bottom 61, the blade nearest to said orifice sweeping the material ahead of it into said orifice upon each actuation of the spider F. Thus, until the contents of the container are practically exhausted, the spider F definitely assures the filling of the pocket d in the measuring member D as said member is retracted for a new charge by the spring 81.

As previously indicated, the pocket d is brought into registration with the orifice 62 in the container bottom 61 at the end of the operative throw of the measuring member D. Thereupon the contents of said pocket gravitate through said orifice 62 and spout 60 into the receptacle 30 embraced by the arms 31, 32. This spout 60 and the mixer stem 28 are both enclosed by the receptacle 30 when it is positioned so that its lip abuts against the surface defined by the lower faces of the container C and motor 21. It will be understood, therefore, that the spout 60 and mixer stem 28 are protected from contamination as well as the interior of the receptacle, when said receptacle is pushed up against abutment surface provided to close the same in its position of use.

A counter 92 of conventional type is employed to record the number of charges of material dispensed from the container C. This counter is mounted within the head B of the standard and the readings therefrom are visible through a slot 93 (Fig. 4) in the wall 14 of said head. The counter actuating member, consisting of a reciprocating bar 94 is yieldingly projected into its extended position by means of a spring 95. Arranged to oppose the action of said spring 95 by engagement with the extreme end of said reciprocating bar 94 is a pin 96 (Fig. 10) which projects from the boss 73 on shaft 64. This pin 96 is so disposed radially of the boss 73 that it will strike and shift the bar 94 against the action of the spring 95 when the lever 75 is swung forward to deliver a charge of material from the dispenser.

To simplify the electric wiring for a battery of my devices, provision is made for plugging one into another so that it is only necessary to connect the first of a series of devices with the source of current. In the base 10 of the standard, opposite the male plug 42 is a receptacle 97 (Fig. 3) which will receive the prongs of the male plug of a second device. This receptacle is connected through wires 98 and 99 with the male plug 42 to which the wires 40, 41 are also connected, as previously described.

Changes in the specific form of my invention, as herein disclosed, may be made within the

scope of what is claimed without departing from the spirit of my invention.

Having described my invention, what I claim as new and desire to protect by Letters Patent is:

1. A dispenser comprising a container having a bottom proper and a false bottom spaced thereabove, said bottoms having orifices therein relatively offset and said container having a curved wall surface between said bottoms, a segmental measuring member disposed within the space between said bottoms, said member being adapted to oscillate about an axis concentric with said curved wall surface and comprising a body, a pair of spaced blades issuing radially therefrom, a curved gate extending in one direction from the upper edge of one blade and a second gate extending in the opposite direction from the lower edge of the other blade, the outer edges of said blades and gates being adapted to skirt said curved wall, the space between said blades, body and wall constituting a measuring pocket open at top and bottom thereof, the same being adapted to register with the orifice in the false bottom in one extreme position of said member to receive a charge of material from the container and adapted to register with the orifice in the bottom proper in the other extreme position of said member for delivery of the charge from said pocket, the lower gate serving to close the orifice in the bottom proper when said pocket is positioned to receive material through the orifice in the false bottom and the upper gate serving to close the orifice in the false bottom when the pocket is positioned to discharge its contents through the orifice in the bottom proper, and means for oscillating said measuring member.

2. A dispenser comprising a container having a bottom proper and a false bottom spaced thereabove, said bottoms having orifices therein relatively offset from each other, an upright shaft journaled in the container structure, a segmental measuring member keyed to said shaft between said bottoms and formed with a pocket therein open at top and bottom thereof, means for rocking the shaft to oscillate said member and thereby shift the pocket therein from one extreme position to the other, the one bringing the pocket into register with the orifice in the false bottom and the other bringing said pocket into register with the orifice in the bottom proper, said segmental member being formed with gates, one for the orifice in the false bottom and one for the orifice in the bottom proper, said gates being adapted to close their respective orifices when the pocket is shifted out of register therewith.

3. A dispenser comprising a container having a bottom proper and a false bottom spaced thereabove, said bottoms having orifices therein relatively offset from each other, an upright shaft journaled in the container structure, a measuring member keyed to said shaft between said bottoms and formed with a pocket therein open at top and bottom thereof, means for rocking the shaft to oscillate said member and thereby shift the pocket therein from one extreme position to the other, the one bringing the pocket into register with the orifice in the false bottom and the other bringing said pocket into register with the orifice in the bottom proper, an agitator on the shaft oscillated thereby for breaking up material within the container, and a rotating filling member beneath said agitator, said member having a ratcheting connection with said shaft and adapted to progress a step upon each

throw of the measuring member bringing the pocket thereof into register with the orifice in said false bottom, said filling member serving to sweep the contents of said container adjacent the false bottom thereof into the orifice in said false bottom as the pocket of the measuring member progresses into register with said orifice.

4. A dispenser comprising a container for comminuted material, said container having a bottom with a discharge orifice therein, an upright shaft within the container, means for rocking said shaft, a spider within the container consisting of a hub and a plurality of radial blades disposed edgewise relative to the bottom of said container, said hub being ratcheted upon said shaft to effect a turning movement of the spider in one direction upon the turning of the shaft in the same direction, the blades of said spider serving progressively to feed material to said orifice, and an agitator above said spider, the same being mounted on said shaft and adapted to oscillate therewith.

5. A dispenser comprising a container having a bottom with a discharge orifice therein, a rocking element, a closure for said orifice actuated by said element and adapted upon one throw thereof to clear said orifice and upon the reverse throw to obstruct said orifice, a rotating member within the container for feeding material to said orifice, said member being actuated by said rocking element and progressively advanced a step at a time as said rocking element is turned in a direction to clear said orifice, and an oscillating agitator disposed within said container above said rotating member, said agitator being swung in opposite directions by said rocking element.

6. A dispenser comprising a container having a bottom proper and a false bottom spaced thereabove, said bottoms having orifices therein relatively offset from each other, an upright shaft journaled in the container structure, a measuring member keyed to said shaft between said

bottoms and formed with a pocket therein open at top and bottom thereof, means for rocking the shaft to oscillate said member and thereby shift the pocket therein from one extreme position to the other, the one bringing the pocket into register with the orifice in the false bottom and the other bringing said pocket into register with the orifice in the bottom proper, a pocket filling member rotatable above the bottom proper and adapted to be rotated by said shaft when it is turned in one direction and adapted to remain idle when said shaft is turned in the opposite direction, and an agitator on the shaft adapted to be swung thereby, through the contents of the container, above the filling member and in a direction opposed to the direction of movement of said filling member.

7. A dispenser comprising a container having a bottom proper and a false bottom spaced thereabove, said bottoms having orifices therein relatively offset from each other, an upright shaft journaled in the container structure, a measuring member keyed to said shaft between said bottoms and formed with a pocket therein open at top and bottom thereof, means for rocking the shaft to oscillate said member and thereby shift the pocket therein from one extreme position to the other, the one bringing the pocket into register with the orifice in the false bottom and the other bringing said pocket into register with the orifice in the bottom proper, a pocket filling member consisting of a hub and a plurality of radial blades disposed edgewise relative to the bottom of said container, said hub being ratcheted on the shaft, whereby said member is rotated by said shaft when the shaft is turned in one direction and left idle when said shaft is turned the opposite direction, and an agitator on the shaft adapted to be swung thereby, through the contents of the container, above the filling member and in a direction opposed to the direction of movement of said filling member.

THEODORE M. COSTAKOS.
